UNITED STATES PATENT OFFICE.

GEORGE S. HENSEL, OF PHILADELPHIA, PENNSYLVANIA, ASSIGNOR TO THE HENSEL, COLLADAY COMPANY, OF PENNSYLVANIA.

DESIGN FOR A SKIRT AND SHOE PROTECTOR.

SPECIFICATION forming part of Design No. 31,913, dated November 28, 1899.

Application filed October 19, 1899. Serial No. 734,126. Term of patent 14 years.

To all whom it may concern:

Be it known that I, GEORGE S. HENSEL, a citizen of the United States, residing in the city and county of Philadelphia, State of Pennsylvania, have invented and produced a new and original Design for Skirt and Shoe Protectors, of which the following is a specification, reference being had to the accompanying drawings, forming part thereof.

10 The leading feature of my design for a skirt and shoe protector is a protector as hereinafter described, and shown in the accompanying drawings, in which latter—

15 Figure 1 represents an elevation of a piece of skirt and shoe protector embodying my design. Fig. 2 represents a section thereof on line $\alpha\alpha$, Fig. 1.

In the drawings, A designates a piece of a skirt and shoe protector, the same consisting of the body B, the brush C, pendent therefrom, top edging D, and the facing E, the latter having a plain smooth surface of a glossy nature.

Having thus described my invention, what I claim as new, and desire to secure by Letters 25 Patent, is—

The design for a skirt and shoe protector substantially as shown and described.

GEORGE S. HENSEL.
